(57) **CLAIM**

The ornamental design for a bed, as shown and described.

DESCRIPTION

FIG. 1 is a front and right side perspective view of a first embodiment of a bed showing my new design;

FIG. 2 is a front elevation view thereof;

FIG. 3 is a right side elevation view thereof, the left side being a mirror image;

FIG. 4 is a rear elevation view thereof;

FIG. 5 is a top plan view thereof;

FIG. 6 is a front and right side perspective view of a second embodiment of a bed showing my new design;

FIG. 7 is a front elevation view thereof;

FIG. 8 is a right side elevation view thereof, the left side being a mirror image;

FIG. 9 is a rear elevation view thereof; and,

FIG. 10 is a top plan view thereof.

The broken lines shown in the drawings illustrate portions of the article that form no part of the claimed design. The second embodiment is shown with a symbolic break, and those portions of the article between the break lines form no part of the claimed design.

1 Claim, 10 Drawing Sheets
